UNITED STATES PATENT OFFICE.

JAMES BURNS, OF SAN ANTONIO, TEXAS.

IMPROVEMENT IN MOLDS FOR SEWER-BUILDING.

Specification forming part of Letters Patent No. 222,863, dated December 23, 1879; application filed August 1, 1879.

To all whom it may concern:

Be it known that I, JAMES BURNS, of San Antonio, in the county of Bexar and State of Texas, have invented a new and Improved Mold for Sewer-Building, of which the following is a specification.

My improvements relate to molds or centerings for use in building sewers of concrete, artificial stone, or brick; and the invention consists in a collapsible mold, made of convenient length, and of the cross-sectional shape required for the sewer, and fitted on wheels, whereby the sewer can be built in sections around the mold and the mold moved along the trench from time to time as the sections are completed.

The construction and operation will be more particularly explained with reference to the accompanying drawings, wherein—

Figure 1 is a vertical longitudinal section of my sewer-mold as applied to use. Fig. 2 is a vertical cross-section of the same. Fig. 3 is a similar view, showing the mold collapsed.

Similar letters of reference indicate corresponding parts.

A is my improved mold or centering, which is constructed of suitable length—say, ten or fifteen feet—and of oval or other form in cross-section.

The frame consists of a top cross-rib, a, at each end, to which ribs are pivoted vertical side ribs, b, that have their lower ends connected by toggle-bars c, which retain and brace the ribs b when the mold is expanded.

The ribs a b are covered by a sheathing, d, of wooden slats or sheet metal, except at the bottom, which is left open.

Extending lengthwise through the mold, and sustained by ribs a, is a shaft, d', from which chains or ropes i extend to the jointed bars c.

The ends of shaft d' project beyond the mold, and are formed with crank-handles, by which the shaft can be turned to wind the chain, and thereby draw the sides of the mold inward.

The mold is supported on wheels e, that are fitted in suitable supports at the lower ends

of the side ribs. These wheels facilitate the labor of shifting the mold as the work progresses.

In building sewers with this mold, the bottom or base, of stone or concrete, is first laid in the trench at the required grade, and when this is set the mold is placed thereon and the sides and crown of the sewer formed around it to the length of the mold. A head, f, is attached to the end of the mold by screws or other fastenings, and projects as a flange; or, when a sewer is commenced, a head will be used at each end of the mold, and the material laid up between them to form the first section of a uniform thickness. When the section is completed the head or heads f will be removed and the shaft d' turned to draw the sides of the mold inward. This action allows the mold to drop down, so that the sides and crown are relieved, and the mold may be then drawn out to the position required for the next section, and expanded by relieving the chain.

There are springs g attached to bars c and ribs b, which tend to draw bars c downward and expand the mold. There are also braces h, hung on ribs a, which, when the mold is collapsed, catch on pins in side ribs, b, so as to give rigidity to the mold while it is being withdrawn.

To prevent the sides of the mold from being forced inward when the sides of the sewer are rammed, the joint of the bars c may be fitted to drop slightly below the center-line when the sides are expanded, and the springs g aid in accomplishing the same object.

By the use of the mold described the sewer may be built rapidly to any grade, with top and sides of uniform thickness, without joints, and with a smooth interior surface.

The trench may be filled as the work progresses up to the crown of the sewer, and the side walls thus strengthened while the material is setting.

Having thus fully described my invention, I claim as new and desire to secure by Letters Patent—

1. The collapsible mold or centering A,

mounted on wheels or rollers, substantially as and for the purposes set forth.

2. A collapsible mold or centering for sewer-building, consisting of cross-ribs *a*, jointed side ribs *b*, sheathing *d*, toggle-bars *c*, head *f*, shaft *d'*, and chain or rope *i*, combined for operation substantially as described.

3. In a collapsible sewer-mold, the combi-

nation, with the jointed bars or braces *c*, of springs *g*, substantially as and for the purposes described.

JAMES BURNS.
